STAMP CANCELLER

Ernest Richmond, Chicago, Ill.

Application May 1, 1935, Serial No. 19,312

1 Claim. (Cl. 101—330)

This invention appertains to new and useful improvements in means for cancelling postage stamps in post offices.

It has been found that in the use of dating and cancelling machines which automatically date and cancel the stamps on letters, frequently the cancelling mechanism does not touch the stamp because of the placement thereof. Therefore, the stamp is caught by the assorter who uses a dauber saturated with ink which he daubs on the stamp. Since this makes the letter very unpresentable and makes the stamp unsuitable for stamp collectors, its use is much resented by laymen.

The principal object of the present invention is to provide a small canceller which can be conveniently used by the assorter as he arrives at letters uncancelled.

Other important objects and advantages of the invention will become apparent to the reader of the following specification.

In the drawings:

Figure 1 is a front elevational view of a stamped envelope cancelled by the use of the present invention.

Figure 2 is a side elevational view of the device shown attached to a wall.

Figure 3 is a side elevational view of the device shown attached to a wall with the cancelling roll elevated.

Figure 4 is a side elevational view of the inking roll.

Figure 5 is a front elevational view of the inking roll.

Figure 6 is a vertical sectional view through the device.

Figure 7 is a vertical transverse sectional view through the device with the rolls removed.

Figure 8 is a front elevational view of the cancelling roll.

Figure 9 is a longitudinal sectional view taken substantially on line 9—9 of Figure 8.

Figure 10 is a perspective view of the cancelling roll carrier.

Figure 11 is a front elevational view of a slightly modified form of cancelling roll showing the ribs extending longitudinally of the roll.

Referring to the drawings wherein like numerals designate like parts, it can be seen that the invention consists of an ink receptacle 5 having the upper portion of its front open as at 6 and the upper edges of its side walls inclined as at 7. The back wall 8 extends upwardly as at 9 and openings 10 are provided in this back wall to receive securing means 11 whereby the receptacle

can be secured to a wall or other similar construction.

The side walls are provided with inclined slots 11 opening through the upper edges 7 and these slots 11 receive the pintles or trunnions 12 of the interior roll 13 which when in the position shown in Figure 6 is partly immersed in the ink of the receptacle.

A carrier for the cancelling roll 14 consists of the plate 15 provided with depending side flanges 16 which flanges as shown in Figure 10 are provided adjacent one of its ends with an extension 17 having an opening 18 therein and at its opposite end with an opening 19. Through the openings 19 and a corresponding opening in the side walls of the receptacle 5 is disposed a pivot pin 20, while a shaft or pin 21 is disposed through the openings 18 and through the cancelling roll 14. In this manner the cancelling roll is supported in the position substantially shown in Figure 6 engaging against the inking roll 13.

The cancelling roll 14 is provided with circumferentially extending ribs 22 arranged in equal longitudinal spaced relation, while the inking roll 23, a modification of the roll 14 is provided with longitudinally extending circumferentially spaced ribs 24.

It can now be seen that with the parts in the relationship shown in Figure 6, a letter need only be placed on the plate 15 and pulled downwardly over the marker roll 14 and the roll will of course transmit cancelling lines to the stamp of the envelope.

While the foregoing specification sets forth the invention in specific terms, it is to be understood that numerous changes in the shape, size, and materials may be resorted to without departing from the spirit and scope of the invention as claimed hereinafter.

Having described the invention, what is claimed as new is:

A device comprising a receptacle provided with a bottom wall and side walls, said side walls being provided with vertical slots therein, an inking roll provided with lateral pintles for disposition through said slots, a cancelling roll, a pivotal carrier for said cancelling roll, said pivotal carrier consisting of a plate provided with a pair of depending flanges pivotally connected to said side walls, said flanges extending beyond one end of the plate and adapted to support said cancelling roll, said plate being disposed over the upper end of said slots to prevent displacement of the pintles therefrom.
